UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,898, dated November 14, 1893.

Application filed October 7, 1893. Serial No. 487,519. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental figures formed of leaves, flowers and scrolls 10 conventionalized, and placed at regular distances apart over the surface of the paper, as represented in the accompanying drawing. The border or upper portion of the said design is also formed of similarly shaped ornamental figures with ornamental scrolls spring- 15 ing from near the base of each figure and connecting similar ornaments, forming a continuous border.

What I claim is—

1. The design for wall paper herein shown 20 and described.

2. In the design for wall paper, the border herein shown and described.

Witness my hand this 2d day of October, 1893.

CHARLES BOOZE.
